DESIGN FOR A FINGER RING

Frederick J. Gaertner, Maplewood, N. J.

Application July 25, 1936, Serial No. 64,046

Term of patent 14 years

To all whom it may concern:

Be it known that I, Frederick J. Gaertner, a citizen of the United States, and a resident of Maplewood, in the county of Essex and State of New Jersey, have invented a new, original, and ornamental Design for a Finger Ring, of which the following is a specification, reference being had to the accompanying drawing forming part thereof.

Figure 1 is a front elevation of a finger ring showing my new design.

Figure 2 is a top plan view thereof, Figure 3 is a side elevation of the ring, and Figure 4 is a transverse sectional view on the line 4—4 of Figure 2.

I claim:

The ornamental design for a finger ring, as shown.

FREDERICK J. GAERTNER.
